CLAIM

The ornamental design for a cricket ball, as shown and described.

DESCRIPTION

FIG. 1 is a top and side perspective view of a cricket ball showing our new design;

FIG. 2 is an exploded view thereof;

FIG. 3 is a front view thereof;

FIG. 4 is a back view thereof;

FIG. 5 is a right side view, the left side being a mirror image thereof;

FIG. 6 is a top view thereof;

FIG. 7 is a bottom view thereof; and,

FIG. 8 is a cross sectional view taken on line 8-8 of FIG. 4.

The broken lines are included for the purpose of illustrating features of the cricket ball that form no part of the claimed design.

1 Claim, 4 Drawing Sheets
